UNITED STATES PATENT OFFICE.

JOHN C. BARR, OF TACOMA, WASHINGTON.

CIRCULAR FLOOR CONVEYER.

No. 842,056.

Specification of Letters Patent.

Patented Jan 22, 1907.

Application filed January 18, 1906. Serial No. 296,418.

To all whom it may concern:

Be it known that I, JOHN C. BARR, a citizen of the United States, residing at the city of Tacoma, in the county of Pierce and State of Washington, have invented certain new and useful Improvements in Circular Floor Conveyers, of which the following is a specification.

My invention pertains to conveyers used to transfer, handle, or store freight or merchandise that may be moved or stored on or across floors of warehouses, wharves, platforms, and decks.

The objects of my invention are, first, to provide a means of receiving freight or merchandise from any means of transportation and delivering it onto a floor or across said floor to other means of transportation; second, to provide a floor conveyer that will be level with a floor, wharf, or deck, said conveyer to be used for moving and transferring freight and merchandise without interfering with the use of the floor for trucking or other purposes; third, to provide a means for receiving, sorting, checking, storing, or transferring large lots and quantities of freight and merchandise, said means being a circular floor conveyer made to revolve by any suitable means of operation, and, fourth, to provide a means whereby freight and merchandise may be received, stored, checked, and sorted, transferred, and delivered with less labor, time, and expense than by the present methods of handling and trucking.

35 I attain these objects by means of the mechanism illustrated in the accompanying drawings, in which—

Figure 1 is a representation of a warehouse, ship, and barge with my invention located in each. Fig. 2 represents a warehouse with my invention located within the same. Fig. 3 represents a cross-section of the floor conveyer, showing its construction and means of operation. Fig. 4 represents a partial plan of a ship partially equipped with my invention, and Fig. 5 represents a cross-section of a ship equipped with my invention on its lower decks.

Similar letters refer to similar parts in the several views.

My invention comprises a circular section of the floor of a warehouse, wharf, platform, or deck so constructed as to be level or flush with the floor, wharf, platform, or deck and so mounted as to be movable by turning in a circular direction. The form and location

of such a movable circular floor-section is indicated at A in Fig. 1, where it is constructed to extend through the warehouse W to the wharf B on one side and the platform C on the other side. This movable circular floor is constructed as indicated in Fig. 3, the floor-planking D being nailed to and carried on wood stringers E E, strengthened and shod by the steel channels F. These stringers are mounted on fixed rollers G G, and the stringers E E are trussed and braced by means of the floor-planking D, nailed thereto, and the truss-rods H H, put in diagonally at proper intervals. The circular floor is kept in place by means of the guide-rollers I, set at proper intervals to prevent the edges of the movable platform from rubbing against the fixed floor on either side. The circular floor is moved or turned by means of the pinion-gear J, engaged with a fixed gear on the side stringer of the circle. The gear J is operated by belt, motor, or other mechanical power and the circular floor thereby turned in either direction, as desired.

A circular floor constructed and operated as herein described and shown provides a floor conveyer on which freight or merchandise may be transferred from a car K to a ship L, or from the ship to the car, or from either ship or car to the warehouse, or from the warehouse to the car or to the ship. The circular floor conveyer thus forms a means whereby freight and merchandise may be received from one means of transportation and delivered onto a floor or across said floor to other means of transportation. The conveyer being level with the floor will not interfere with the use of the floor for trucking or other purposes. The conveyer constructed and operated as described and shown will be useful for receiving, storing, sorting, and checking, transferring, and delivering freight and merchandise in large lots or quantities. The work by means of my invention can be done with a great saving of time, labor, and expense over the present methods of handling and trucking.

My invention may be confined wholly within a warehouse, as indicated at A' in Fig. 2. The freight or goods can be received from the car and deposited on the conveyer, checked and sorted in transit, and carried to the opposite side, where it can be delivered to the ship and likewise from the ship to the car or to any part of the warehouse. By putting a multiple of conveyers within or

through a warehouse a number of cars of freight may be so handled simultaneously and as fast as it can be received on board other means of transportation on the opposite side. My invention is also designed to be used on the decks of ships and barges, where it may be installed and operated as described and shown in warehouses.

In using my invention on ships and barges

- 10 I purpose not only using a circular floor conveyer, but to use it as a turn-table or turret form of decks that may be constructed on one or more decks of a vessel. This application of my invention is more fully shown at M 15 in Figs. 4 and 5. The floor conveyers in these instances are circular floors, comprising the entire radius of the circle on which they are constructed, thus forming a disk or turret form of floor.
- 20 I purpose where desirable to inclose these circular floors with walls N on the outer circle of the floors and to divide the space inclosed into compartments by means of radial walls O. A hatch P is provided in the floor of one 25 of the compartments of each upper turret, so the lower turret may first be filled. In loading a vessel the lowest turret is first filled, each compartment being filled singly and the conveyer turned round until all are full, 30 when the next turret above may be likewise filled until all are loaded. By means of these 35 separate compartments the freight can be loaded in separate lots or shipments consigned to different ports and be accessible without disturbing any other portion of the cargo. To accomplish the result last mentioned, I purpose introducing side hatches Q 40 in the angles between the turrets. Doors R, opening into any or all of the compartments, give access to each from these angle-spaces, and any compartment may thus be unloaded 45 without disturbing the others.

For the shipment of coal, ores, grain, sand, or gravel the compartments mentioned may 45 be constructed with floors inclined toward the doors opening into the side hatches, as indicated at S, thus causing the contents to gravitate toward the hatch when the door is 50 opened, from where it can be hoisted, and thereby save the expense of shoveling that kind of freight.

The above mentioned and described use of turrets with compartments in connection with my circular-floor-conveyer invention is 55 applicable to ships and barges of one or more decks. It is to be observed that I do not claim the use of compartments as strictly a part of my invention, but mention the use of

them to show their practical use and application to my newly-invented circular floor conveyer.

I am aware that prior to my invention other platform conveyers having straight and circular movements have been used; but my conveyer is designed to run flush or level with the floor and is made rigid and of sufficient strength to receive and convey heavy loads and in this regard is novel, inasmuch as it differs materially from previous inventions of this character.

Having described my invention, what I claim as new, and desire to secure by Letters Patent, is—

1. A circular floor conveyer, comprising a circular traveling floor set level with a floor or deck, said floor constructed with stringers and truss-rods, and said stringers mounted to travel on fixed rollers, guide-rollers at the side of the outer stringers and a pinion-gear engaging a fixed gear on one of said stringers for turning said circular floor conveyer substantially as described and set forth.

2. A circular floor conveyer comprising a circular non-flexible platform located and capable of traveling within a way on opposite sides of which, both within and outside of the circle described by the way, is a fixed flooring adapted to receive on either side of the platform a load carried by the same, substantially as described.

3. A circular floor conveyer comprising a circular non-flexible platform located and capable of traveling within a way on opposite sides of which, both within and outside of the circle described by the way is a fixed flooring adapted to receive on either side of the platform a load carried by the same, said platform being adapted to travel in opposite directions as desired, substantially as set forth.

4. A circular floor conveyer, comprising a circular platform adapted to travel in opposite directions as desired, and composed of metal-faced stringers, flooring secured to said stringers and forming a rigid, non-flexible surface to the platform, truss-rods connecting and bracing the stringers, and fixed rollers suitably located to have said stringers travel thereon, substantially as described.

In testimony whereof I affix my signature in presence of two witnesses.

JOHN C. BARR.
